UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-PLATE.

1,211,616.

Specification of Letters Patent. Patented Jan. 9, 1917.

Application filed April 16, 1915. Serial No. 21,665.

To all whom it may concern:

Be it known that I, CHARLES J. NASH, a citizen of the United States, and resident of Chicago, county of Cook, and State of Illinois, have invented certain new and useful Improvements in Draft-Plates, of which the following is a specification, and which are illustrated in the accompanying drawings, forming a part thereof.

10 The invention relates to draft plates for railway cars, its object being to provide a form of construction in which there is secured great strength while the massing of metal is avoided.

15 The invention consists in a structure as hereinafter described and as illustrated in the accompanying drawings, in which—

Figure 1 is a view of the draft plate in perspective, Fig. 2 is a front elevation thereof, and Fig. 3 is a sectional view on the broken line 3—3 of Fig. 2.

The improved draft plate comprises front and rear draft and buffing lugs 10, 11, and a central abutment 12, which constitutes a 25 buffing shoulder 13, for a forward gear and a draft shoulder 14 for a rearward gear. A top flange 15 extends throughout the length of the plate, its forward edge being in line with the front faces of the lugs 10, 11, and 30 abutment 12 and its rearward edge being adapted to bear against the sill to which the plate is to be attached. Bearing plates 16, 17, extend forwardly from the lug 10 and similar plates 18, 19 extend rearwardly from 35 the lug 11 and are adapted to lie against the car sill and are apertured to accommodate attaching rivets. The top flange 15 extends to the outer ends of these bearing plates and serves as braces for the lugs 10, 11. Fillets 40 20, 21 similarly brace the lower ends of these lugs. Intermediate of the plates 16, 17, and of the plates 18, 19, there are formed hollow 45 braces 22, 23 for further supporting and strengthening the lugs 10, 11. The abutment 12 is hollow and is provided with a bottom wall 24, the flange 15 constituting its top wall. A horizontal web or partition extends across the chamber of this abutment. The lower portion of the front face of the 50 abutment is open, as shown at 26, this opening extending vertically from the partition

to the bottom wall. The upper portion of the rearward face of the abutment, extending from the partition 25 to the flange 15, is open, as shown at 27. The closed portion 28 55 of the rear face of the abutment 12, being that part which is below the partition 25, constitutes a bearing to engage the car sill and is pierced to accommodate an attaching 60 rivet.

The body portions of the draft plate, indicated by the numerals 29, 30, between the draft and buffing lugs 10, 11, in the abutment 12, is located inwardly from the plane of the several sill-bearing faces and is looped inwardly, as shown at 31, 32, to form limiting stops for the gear followers. A horizontal section 33 of the body portion of the plate between the lug 10 and the abutment 12 and a similar section 34 between the abutment 65 12 and the lug 11 are off-set backwardly to the sill-bearing plane, these sections extending through the limiting stops 31, 32 and being pierced to receive attaching rivets. These backwardly offset sections are located 70 above the horizontal median line of the draft plate and are connected with the portions 29, 30, by webs, as 35, these webs extending to the front faces of the intermediate stops. A bottom flange 36 extends backwardly from the body portions 30 and the intermediate stops 31, 32, to the plane of the 75 sill bearing faces.

In the construction as described, all massing of metal is avoided, the various parts of 85 the plate being of uniform thickness, and great strength is secured by bracing the plate throughout by means of the various flanges, webs and partitions as described, against stresses in all directions.

As that portion of each of the limiting stops 31, 32, lying below the backwardly offset portions 33, 34 of the plate, extends above the median line of the plate and consequently above the axis of the gear with 90 which the plate will be associated, it provides a smooth and extended guide for the gear springs.

I claim as my invention,—

1. A draft plate having draft and buffing 10 lugs with continuous faces, a longitudinal section of the body of the plate being offset

backwardly to form a bearing to engage and be secured to a support, such offset terminating at and being connected with the faces of the lugs.

5. 2. A draft plate having stop lugs and intermediate limiting stops, the body of the plate having a horizontal section lying above

its median line backwardly offset forming a channel in its face extending across the limiting stops, the portion of such stops located below the channel constituting a spring guide. 10

CHARLES J. NASH.
